(57) **CLAIM**

The ornamental design for a hair curler as shown and described.

DESCRIPTION

FIG. 1 is a perspective view of a hair curler showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a perspective view of the hair curler where the hair curler is in a configuration of use.

The broken lines in the drawings depict portions of the hair curler that form no part of the claimed design. The hair curler is shown with a symbolic break in its length; the dot-dash broken lines thereof and the appearance of any portion of the hair curler between the break lines form no part of the claimed design.
